UNITED STATES PATENT OFFICE.

CARL F. BRAUN, OF SAN FRANCISCO, CALIFORNIA.

TWIN STRAINER.

Application filed March 13, 1919. Serial No. 282,259.

To all whom it may concern:

Be it known that I, CARL F. BRAUN, a citizen of the United States, residing at San Francisco, in the county of San Francisco and State of California, have invented new and useful Improvement in Twin Strainers, of which the following is a specification.

This invention relates to a twin strainer and particularly pertains to a device for the purpose set forth in my patent entitled Twin strainer, dated January 15, 1918, bearing the Number 1,253,344.

The present invention is particularly concerned with means for providing a simplified by-pass for controlling separate manifolds and diverting the liquid therefrom through separate strainer units with a minimum amount of friction, said units being housed in a compact case within which the control valve mechanism is mounted and which further insures that the strainers or the valves may be readily removed when desired.

The present invention comprises a pair of parallel strainer units, between which a passageway is formed, with which passageway communication may be established from either or both of the units by means of valves operating transversely to the longitudinal axis of the strainer units, the passageways and ports being straight and affording direct communication.

The invention is illustrated by way of example in the accompanying drawings, in which—

Fig. 1 is a view in side elevation with parts broken away to clearly disclose the relative disposition of the strainers to the control valves.

Fig. 2 is a view in horizontal section through the device, as seen on the line 2—2 of Fig. 1.

Fig. 3 is a view in vertical section through the device, as seen on the line 3—3 of Fig. 1.

Referring more particularly to the drawings, 10 indicates a housing formed on one side with a bolting flange 11. This flange surrounds an intake port 12, which port communicates with a cylindrical valve chamber 13. The central axis of the valve chamber 13 extends horizontally and agrees with the longitudinal center of an upper valve stem 14. This stem passes through an annular valve seat 15, which is mounted on one side of the chamber 13 and thereafter

extends into a bearing 16 mounted outside of the chamber 13, as particularly shown in Fig. 2. Opposite the valve seat 15 in chamber 13, is formed another annular valve seat 17, agreeing with the seat 15 and in alignment therewith.

A double-face valve member 18 is mounted upon the stem 14 and by rotation of the stem, may be caused to alternately register with either one of the seats 15 or 17. The central opening through the seat 15 communicates with an upper passageway 19 and the opening through the seat 17 communicates with an upper passageway 20. The upper passageway 19 is in communication with a cylindrical strainer housing 21 while the passageway 20 is in communication with a cylindrical strainer housing 22. The longitudinal axes of these housings are parallel with each other, and at right angles to the axis of the valve stem 14.

Between the strainer cylinders 21 and 22 is an outlet passageway 23 provided with a suitable bolting flange 24' by which it may be connected to any desired piping. Referring to Fig. 3, it will be noted that the upper passageway 19 surrounding the valve stem 14, does not connect directly with the outlet passageway 23 but as shown in Fig. 2, constantly communicates with the strainer cylinder 21 while the passageway 20 constantly communicates with the cylinder 22. Communication between these two cylinders with the outlet passageway 23 is controlled by a double valve member 24 mounted upon a valve stem 25. This stem is parallel to the valve stem 14 of the valve 18 and operates across the end of the outlet passageway 23. This passageway, as shown in Fig. 1, is in the same vertical plane with the inlet passageway 13 although not in direct communication therewith. The walls of the outlet passageway 23 are provided with valve seats 26 and 27 respectively, against which the valve member 24 may alternately register. The flow opening through the valve seat 26 establishes communication between one end of the cylinder 21 and the outlet passageway while the opening through the valve seat 27 establishes communication between a corresponding end of the strainer cylinder 22 and the outlet passageway.

It will thus be observed that movement of the valve member 18 will act to direct the inflow of liquid to either of the strainer

cylinders 21 or 22 and the movement of the valve member 24 will act to control the outflow of liquid from these two cylinders. The valve mechanism may be of any conventional design but is here shown as comprising a cross-head 28 carried upon bolts 29, the cross-head being threaded to receive the outer threaded end of the valve stem. A hand wheel 30 is mounted upon the outer end of each stem and thus when the hand wheel is rotated, the corresponding stem may be reciprocated through the cross-head and the valve carried thereby moved as desired. The cross-head and its supporting members are mounted upon end caps 31 which seal the upper ends of the valve chambers and which may be taken off by the removal of cap screws 32, thus making it possible to readily repair the valves when desired. In this connection it is also to be noted that the various valve seats are threaded into position and may be easily removed or replaced. The strainer cylinders 21 and 22 are fitted with removable heads 33, particularly shown in Fig. 3. These heads are pivotally and centrally mounted upon swinging cross-arms 34, the cross-arms being pivoted by bolts 35 to brackets 36. The free ends of the cross-arms are adapted to be locked in place by eye-bolts 37 carrying lock-nuts 38. It will thus be seen that the members 33 may be readily removed and access gained to the cylinders 21 and 22. Mounted within each of these cylinders is a cylindrical screen 39. These screens are of a length short of that of the cylinders and are fitted into position in the manner indicated by dotted lines in Fig. 3. It will thus be seen that the passageways 19 and 20 communicate with the upper ends of the screens and are separated from the main compartment of the cylinders by means of a wall 40. The screens are made with an upper flange 41 which tends to form a seal between them and the wall while the opposite end of each screen is provided with a head 42 carrying a centering pin 43. This pin extends into a centering boss 44. One of these members is formed in the bed end of each of the cylinders 21 and 22 and concentric therewith. The screens are held in position by means of triangular-shaped springs 45 which are carried upon the end flange 41 of each screen and are adapted to be pressed against by the cover members 33 of the cylinders, thus holding the screens in position and permitting them to be easily removed when required.

In operation of the present invention, a fluid is admitted to the housing 10 through the intake port 12. It then passes into the chamber 13. If the valve member 18 stands midway between the valve seats 15 and 17, the fluid will flow in both directions and will thus circulate through the passageways

19 and 20, entering the upper ends of each of the screen cylinders. It will then pass through the wall of the screen and if the valve member 24 is standing away from its valve seats 26 and 27, the fluid will flow into the outlet passageway 23 and then to the connections with which the bolting flange 24' is secured. It will be evident that by moving the valve member 18 to cause it to register with either of its seats 15 or 17, the fluid may be diverted from either of the passageways 19 or 20 to the opposite passageway and the entire volume of fluid caused to circulate through one cylinder 21 or 22 and the screen element 80 therein. By closing the corresponding valve opening of the valve member 24, one of the screens may be completely eliminated, if desired, for the purpose of repairs or other reasons.

It will thus be seen that the device here disclosed is embodied within a very compactly designed structure which permits direct operation of the valves and selective operation of the screening elements, at the same time insuring that the valves and screening elements may be separately removed and repaired without discontinuance of the operation of the structure.

While I have shown the preferred form of my invention, it will be understood that various changes in the combination, construction and arrangement of parts may be made by those skilled in the art, without departing from the spirit of the invention as claimed.

Having thus described my invention, what I claim and desire to secure by Letters Patent is—

1. In a twin strainer, a pair of vertical screen housings, a pair of horizontal and superimposed valve housings formed on one side of the screen housings, each valve housing having a pair of passages extending therefrom, a passage of the upper valve housing communicating with the upper end of each screen housing and a passage of the lower valve housing communicating with the lower end of each screen housing, a screen member in each of said screen housings, an inlet connection for one of the valve housings and an outlet connection for the other valve housing, and a valve in each valve housing whereby the passages of each housing leading to the screen housings may be alternately closed or opened.

2. In a twin strainer, a pair of vertical screen housings, a pair of horizontal and superimposed valve housings formed on one side of the screen housings, each valve housing having a pair of passages extending therefrom, a passage of the upper valve housing communicating with the upper end of each screen housing and a passage of the lower valve housing communicating with

the lower end of each screen housing, a screen member in each of said screen housings, an inlet connection for one of the valve housings and an outlet connection for 5 the other valve housing, said outlet being disposed on one side of the screen housings, opposite to that upon which the valve housings are formed and the inlet being formed in the valve housing with which it communicates, and both inlet and outlet being further disposed in substantially the same horizontal plane.

3. In a twin strainer, a pair of vertical screen housings, a pair of horizontal and 15 superimposed valve housings formed on one side of the screen housings, each valve housing having a pair of passages extending therefrom, a passage of the upper valve housing communicating with the upper end 20 of each screen housing and a passage of the lower valve housing communicating with the lower end of each screen housing, a screen member in each of said screen housings, an inlet connection for one of the valve 25 housings and an outlet connection for the other valve housing, said outlet connection being disposed on the side of the screen housing opposite to the side upon which the valve housings are formed and communicating 30 with its valve housing through a passageway formed between the screen housings, and said inlet connection being formed in the valve housing with which it communicates.

35 4. In a twin strainer, a pair of vertical cylindrical screen housings, a hinged top for each screen housing, a pair of valve housings formed on one side of the screen housings and at right angles thereto, one 40 valve communicating with the upper portion of each screen housing and the other valve communicating with the lower portion of each screen housing, an outlet connection for one of the valve housings and 45 an inlet connection for the other valve hous-

ing, a valve in each valve housing by which the passages of each valve communicating with the screen housings may be alternately closed or opened, a cylindrical screen in each screen housing of less diameter than the inside diameter of the screen housings, an upwardly bowed spring member having its opposite ends secured to the opposing sides of each screen member, and its bow portion adapted to engage the top of the screen 50 housing when closed, and means for exerting downward pressure and locking the top of the screen housings whereby the screens are held in a vertical position.

5. In a twin strainer, a pair of vertical cylindrical screen housings, a pair of superimposed valve compartments formed on the sides thereof each of said compartments having two passages, each passage of the upper compartment communicating with an upper 60 portion of the screen housings and each passage of the lower valve compartments communicating with a lower portion of the screen housings, a cylindrical screen in each of said screen housings of less diameter than 65 the inside diameter of the housings, a central boss in the bottom of the screen housings to hold the screens in spaced relation to the screen housing bottom, a bail on the upper end of each screen adapted to co- 70 operate with the top of said screen housings to hold the screens in a vertical position, an inlet connection for one of said valve compartments, an outlet connection 75 for the other compartment, and a valve for 80 each compartment, whereby the passages thereof communicating with the screen housings may be alternately opened or closed.

In testimony whereof I have hereunto set my hand in the presence of a subscribing 85 witness.

CARL F. BRAUN.

Witness:

JOHN F. MILLER.
